UNITED STATES PATENT OFFICE.

MIHRAN M. DOLMAGE, OF WASHINGTON, DISTRICT OF COLUMBIA.

TWO-WAY-REPEATER CIRCUITS.

1,272,022.

Specification of Letters Patent.

Patented July 9, 1918.

Continuation in part of applications Serial Nos. 30,664, 30,665, 30,666, and 30,667, filed May 26, 1915. This application filed November 8, 1916. Serial No. 130,303.

To all whom it may concern:

Be it known that I, MIHRAN M. DOLMAGE, a citizen of the United States, residing at Washington, District of Columbia, have invented certain Improvements in Connection with Two-Way-Repeater Circuits, of which the following description, in connection with accompanying drawings, is a specification.

This invention has for its object the amplification and transmission of speech currents in both directions. It utilizes for this purpose voice operated circuit changing means, so as to prevent the so-called "singing" of the two-way-repeater system, by controlling the circuits of this system and establishing them accurately with reference to the desired direction at speech transmission. Circuit changing means, voice controlled in their operation, have heretofore been used. This invention differs however from previous inventions in that it does not require the operation of a switch, voice controlled or otherwise, for putting into communication the two terminating telephone stations. In the system described herein the terminating stations are normally connected together through the two-way repeater circuit, which repeater circuit is in normally full repeating relation in both directions.

A further important advantage of the system described herein consists in the utilization of devices for amplifying the voice currents so that the control of the circuit changing means by the voice currents, may be made certain and practically operative.

The use of such amplifying devices has been indicated in conjunction with the particular two-way repeater circuit shown in attached drawings, but it is clear that such devices may be used with any other two-way repeater circuits which require for their proper operation the utilization of voice operated circuit changing means. A practical solution is shown in the utilization of a device of the type known as an "audion," which can be made to amplify alternating currents of voice frequencies and convert these currents into direct current. It then becomes possible to use direct current electromagnetic relays, which usually can be made more sensitive than electromagnetic alternating current relays, for the purpose of securing the proper repeating relations in both directions.

This invention is illustrated in the drawings, as follows:—Figure 1, represents one form of circuit arrangement for carrying out my invention. Fig. 2, shows electromagnetic type amplifiers associated with the alternating current type control relays of the arrangement of Fig. 1. Fig. 3, shows an "audion" arranged for amplifying and converting the alternating currents of speech frequencies into direct current, associated with direct current electromagnetic control relays. Fig. 4, shows a different association of the automatic control relay circuits with the two-way repeater circuit. Fig. 5, shows a different association of the receiving circuits of the two one-way repeaters from that shown in Fig. 1, Fig. 2, Fig. 3, and Fig. 4. Fig. 6, shows the same arrangement for the receiving circuit of the two one-way repeaters as shown in Fig. 5, but a different association of the automatic control relay circuits in the two-way repeater circuit. Fig. 7, shows a third modification in the association of the receiving circuits of the two one-way repeaters and of the automatic control circuits which are wired as diagonals of "bridge" arrangements. Fig. 8, shows a similar arrangement to that shown on Fig. 7, except for the difference in the combination of the secondary windings of the receiving circuits. In Fig. 9, the receiving circuits of the two one-way repeaters are still shown as in Fig. 7, but the secondary windings of the automatic control relay circuits are differently combined. In Fig. 10, the arrangement is similar to that shown in Fig. 8, but is different in the association of the automatic control circuits. Fig. 11, shows a still different association of the automatic control relay circuits with the receiving circuits in the Wheatstone "bridge" arrangements. Fig. 12, shows the same arrangement for the automatic control circuits as in Fig. 11, but differs from this figure in the arrangement, in parallel, of the receiving circuits of the two one-way repeaters, instead of the series arrangement shown in Fig. 11. Fig. 13, shows a circuit arrangement similar to that shown on Fig. 11, but different in the association of the secondary windings of the automatic control circuits from that shown on Fig. 11.

Referring first to Fig. 1, of the drawings, G and H, are the ends of two subscriber, trunk, or toll lines between which is in-

stalled the two-way repeating equipment. A₁ and A₂ represent diagrammatically one-way repeaters. Repeater A₁ is arranged for "repeating" speech currents traveling in the direction from H to G and repeater A₂ for "repeating" in the opposite direction, viz., G to H. Repeaters A₁ and A₂ may be any repeaters known to the art. For reasons of convenience in graphical representation electromagnetic type repeaters of ordinary construction, consisting in each case of an electromagnet operating a microphone, have been shown. Line H connects through primary windings 5 and 6 and secondary windings 7 and 8 of receiving circuit of repeater A₁, to the energizing portion of repeater A₁. The reinforcing portion or transmitting circuit of the same repeater is connected in a "bridge" arrangement, being wired as one arm of the "bridge" in series with one primary winding 12 of automatic control relay circuit D₁. "Balancing" repeater circuit B₁ represents another arm of the "bridge" and is wired in a series with a second primary winding, winding 11 of automatic control relay circuit D₁. Line G is wired as a diagonal of this "bridge" between the junction points of windings 11 and 12 and the junction points of the reinforcing portion of repeater A₁ and its "balancing" electrical circuit B₁. The energizing portion of repeater A₂ is connected inductively through secondary windings 17 and 18 and primary windings 15 and 16 of a second transformer or a "receiving circuit" across line G in series with the "bridge" arrangement above described. The reinforcing portion of this same repeater, repeater A₂ is connected in a second "bridge" arrangement, being wired as one arm of this "bridge" in series with a primary winding, winding 2 of automatic control relay circuit D₂. "Balancing" repeater circuit B₂ represents another arm of this same "bridge" and is wired in series with a second primary winding, winding 1, of automatic control relay circuit D₂. Line H is wired as a main diagonal of the "bridge" between the junction points of windings 1 and 2 and junction points of the reinforcing portion of repeater A₂ and its "balancing" electrical circuit B₂. This second "bridge" arrangement, just described, is wired across line H in series with a transformer or receiving circuit, already referred to, which connects inductively through its primary windings 5 and 6 and secondary windings 7 and 8, the energizing portion of repeater A₁ with line H. To complete the description of the circuit arrangement shown on Fig. 1, secondary windings 13 and 14 of automatic control relay circuit D₁ associated with primary windings 11 and 12, connect in series with each other and with automatic control relay C₁. Likewise, secondary windings 3 and 4, of auto-

matic control relay circuit D₂, respectively associated in inductive relation with primary windings 1 and 2, connect in series with each other and with automatic control relay C₂. Contact 9, controlled by this same relay has been shown as arranged to short circuit the energizing portion of repeater A₁. Contact 10 of automatic control relay C₁ has been shown as arranged to short circuit the energizing portion of repeater A₂. The typical feature of the arrangement shown in Fig. 1 consists in the use of the two "bridge" arrangements which have been described in detail. It is proposed to design the various component parts of the two "bridge" arrangements so that for incoming non-amplified speech currents, reaching the two-way repeater circuit by line G, the electromotive forces induced in the two secondary windings 13 and 14 of automatic control relay circuit D₁ will be equal in amplitude and opposite in direction, will neutralize each other, no resultant current therefore flowing through automatic relay C₁. Such a result will be secured if the impedances of primary windings 11 and 12 are properly proportioned to the mutual impedance between the same windings and secondary windings 13 and 14, respectively. The above necessary and sufficient relation may be expressed in a more concrete manner by the formula.

$$\frac{Z_1}{pM_1} = \frac{Z_2}{pM_2}$$

where

Z₁=series impedance of winding 11 (when its associated secondary winding 13 is open) and of the transmitting circuit of "balancing" repeater B₁.

pM₁=mutual impedance between windings 11 and 13.

pM₂=mutual impedance between windings 12 and 14.

Z₂=series impedance of winding 12 (when its associated secondary winding 14 is open) and of the transmitting circuit of repeater A₁.

As a specific case for a "balanced" condition, we may make

$$\frac{Z_1}{pM_1} = \frac{Z_2}{pM_2}$$

To satisfy the relation as expressed by the above formula it will be preferable to use for the "balancing" electrical circuit B₁, a repeater B of the exact type and characteristics as repeater A₁, as in such a case the "balancing" may be made very accurate.

In the same manner for incoming non-amplified speech currents reaching the two-way repeater circuit via line H, the elec-

tromotive forces induced in the two secondary windings 3 and 4, of automatic control relay circuit D_2 , will neutralize each other, no resultant current therefore flowing through 5 automatic relay C_2 . To secure this result the "bridge" arrangement, of which automatic control relay circuit D_2 forms a part, must be designed in a manner exactly similar to that described in connection with the design 10 of the "bridge" arrangement, of which automatic control relay circuit D_1 forms a part.

It will be evident from an examination of the two "bridge" arrangements just described that when alternating currents of 15 speech frequencies have been amplified, by repeater A_1 , for instance, and are traveling toward line G, as shown in Fig. 1, the electromotive forces induced in windings 13 and 14 of automatic control relay circuit D_1 , on 20 account of the flow of the amplified alternating currents through primary windings 11 and 12, will be in the same direction, will reinforce each other, and result in producing a flow of current through control relay 25 C_1 . For reasons of symmetry the alternating currents of speech frequency, amplified by repeater A_2 and traveling toward line H, will result finally in producing a flow of current through control relay C_2 . It is 30 proposed to have relays C_1 and C_2 made sufficiently sensitive to respond to the amplified voice currents.

In a system, described above in detail, the following operation will obtain: When the 35 comparatively weak or attenuated speech currents reach the two-way repeater circuit via line G, repeater A_2 will be energized through primary windings 15 and 16 and secondary windings 17 and 18 of the transformer or "receiving circuit" associated with this line. Furthermore, a portion of these 40 attenuated currents will flow through windings 11 and 12 of automatic control relay circuit D_1 , through the reinforcing or transmitting portion of repeater A_1 and "balancing" repeater or circuit B_1 . In view of the special design of the parts just mentioned which are associated together in a "bridge" arrangement, the electromotive 45 forces induced in windings 13 and 14 will be equal in amplitude and opposite in direction. There will be no current flow in windings of relay C_1 , which will consequently remain in its non-operated normal 50 position. Repeater A_2 has, however, been energized as mentioned, and will impress an electromotive force through its reinforcing portion or transmitting circuit upon one 55 arm of the "bridge" arrangement which is in series with primary winding 2 of automatic control relay circuit D_2 . It will also impress an electromotive force upon primary winding 1 of circuit D_2 , "balancing circuit" B_2 , line H and also upon the energizing portion of repeater A_1 through pri-

mary windings 5 and 6 and secondary windings 7 and 8 of the transformer associated with line H. Amplified speech currents will therefore flow over line H. Repeater A_1 , however, will not be operated. If it did, 70 the two-way repeater circuit would be "singing", or producing upon the telephone lines G and H a "reactive noise". It will not operate as the flow of voice currents in primary windings 1 and 2 will induce two electromotive forces in windings 3 and 4 which are in the same direction. There will be, therefore, a current flow in control relay C_2 . This relay will operate and through contacts 9 it controls short circuit of the energizing portion of repeater A_1 and render this repeater inoperative. 75

The operation of the circuit, illustrated on Fig. 1, for speech currents reaching the two-way repeater circuit via line connection 80 H will be exactly similar to the operation just described for speech currents reaching the two-way repeater circuit via line connection G. This is clearly evident since the two-way repeater circuit arrangement shown 85 on Fig. 1 is a symmetrical arrangement.

On Fig. 1, control relays C_1 and C_2 have been shown as short circuiting the energizing portions of repeaters A_2 and A_1 , respectively. Instead of this arrangement, the 90 contacts controlled by relay C_2 could be arranged equally as well to open circuit the connection between the energizing portion of repeater A_1 and windings 7 and 8 of the transformer associated with line H, and the 95 contact controlled by relay C_1 to open circuit the connection between the energizing portion of repeater A_2 and windings 17 and 18 of the transformer associated with line G. The modification referred to, or equally 100 evident modifications have not been indicated in the drawings, as it has been considered sufficient to illustrate only one way of securing the result aimed at, *viz.*, rendering inoperative repeater A_1 on speech currents traveling in the direction from line G to line H and rendering inoperative repeater 105 A_2 on speech currents traveling in the direction from line H to line G. 110

To make the operation of control relay C_1 115 and C_2 more certain and the design of relays C_1 and C_2 more practical, I associate these with devices for amplifying alternating currents of speech frequencies. An "audion," such as described in a number of U. S. A. 120 patents (U. S. A. Patent 1,128,292 to E. H. Colpitts, &c.), which would have its energizing portion wired in series with the secondary windings of either automatic control relay circuits D_1 or D_2 and its reinforcing portion with relay C_1 or C_2 , respectively associated with circuits D_1 and D_2 , 125 will be adequate for the purpose. Use may be made also of a pliotron as manufactured by the General Electric Company. Fig. 130

2 shows diagrammatically electromagnetic type amplifiers associated with relays C_1 and C_2 , in a two-way repeater circuit of the type shown on Fig. 1, and illustrates the method 5 of association of the amplifiers with the alternating current type automatic control relays C_1 and C_2 .

Alternating current relays are, as is well known more difficult to secure than direct 10 current relays of equal sensitiveness. I have found the use of a device which would convert, or preferably still, which would convert and amplify, the alternating currents of speech frequencies into unidirectional currents, very convenient and practical. Fig. 3 15 illustrates one method of accomplishing this result in a very effective manner, by means of an "audion" arranged, through the use of a properly poled "third" battery, wired between the grid and filament elements of the "audion," to convert and amplify voice currents into direct or unidirectional currents. H. de F. Arnold has disclosed in U. S. A. Patent 1,128,280 the association of parts required to accomplish the result mentioned. 20 No detail description of the theory of the arrangement is therefore needed in connection with this specification. To carry out the arrangement referred to above into effect, windings 3 and 4 of automatic relay circuit 25 D_2 are wired in series between the grid and filament elements of the "audion," in series with a battery having its negative pole connected to the grid. The potential of the 30 "third" battery required is determined by the actual type of "audion" bulb used. Direct current electromagnetic relay F_2 , which replaces relay C_2 of automatic control relay circuit D_2 , is wired in the circuit between 35 the filament and plate elements of the "audion." With this arrangement there is a steady flow of direct or unidirectional current through relay F_2 . In order to prevent the operation of relay F_2 by this current, I 40 wire across the terminals of this relay a battery through an adjustable resistance. This battery is so poled as to tend to neutralize the effect of the steady current due to the main battery wired between the plate 45 and filament elements of the "audion" upon relay F_2 as shown. By adjusting the variable resistance in series with this auxiliary battery, it is possible to effect a complete neutralization. Under these conditions, and 50 with no flow of alternating currents in the circuit of the secondary windings 3 and 4 of circuit D_2 , there will be no flow whatever of current through windings of relay F_2 , which will remain unoperated. However, 55 when the voice currents amplified by repeater A_2 flow through windings 1 and 2 of circuit D_2 toward line H , then there will be an alternating current electromotive force impressed between the grid and filament elements of the "audion." A flow of unidirectional

current, due to the converted and amplified voice currents will result in windings of relay F_2 . Relay F_2 will operate, and through contact 9 it controls, render inoperative repeater A_1 . In a similar manner 70 alternating current relay C_1 of Fig. 1, may be replaced with the combination of direct current relay and a device for converting and amplifying alternating currents into unidirectional currents. 75

The drawings 4 to 13, indicate certain modifications in the association of the various parts of the two-way repeater circuit shown in Fig. 1, the fundamental underlying ideas remaining however the same. Fig. 4, 80 corresponds to only one-half of the circuit shown on Fig. 1, the omitted part being entirely symmetrical. In this figure the secondary windings of automatic control circuit D_2 , instead of being wired in series with each other and with control relay C_2 , are wired in parallel with each other and with relay C_2 . In this case the general relation indicated for securing a "balance" in the "bridge" arrangement of Fig. 1 will not 85 hold. The balance will be obtained, however, when primary winding 1 is equal in every respect to primary winding 2, secondary winding 3 is equal in every respect to secondary winding 4, and the impedance 90 of the reinforcing portion of repeater A_2 is made equal to the impedance of the "balancing" electrical circuit or repeater B_2 . 95

Fig. 5 shows for one-half of the circuit of Fig. 1, the omitted part being entirely symmetrical in construction, the transformer associated with line H wired directly across line H , in parallel with the "bridge" arrangement involving automatic control relay circuit D_2 , reinforcing portion of repeater A_2 and "balancing" electrical circuit B_2 . In the previous figures, this transformer was shown wired in series with this same "bridge" arrangement. The balance 100 for the "bridge" arrangement, on incoming 100 non-amplified speech currents from line H , is obtained when the relation indicated in conjunction with Fig. 1 is satisfied. To render inoperative repeater A_1 when speech currents are traveling in the direction from 105 line G to line H , contacts 9 controlled by relay C_2 are arranged to open circuit the connection between the energizing portion of repeater A_1 and windings 7 and 8 of the 110 transformer associated with line H . 115

Fig. 6 shows one-half of the two-way repeater circuit, the omitted part being entirely symmetrical in construction, a modification of the circuit shown in Fig. 5. The secondary windings of automatic control relay circuit D_2 are wired in parallel with each other and with relay C_2 , instead of being wired in series with each other and with relay C_2 , as in Fig. 5. The conditions of 120 "balance" for the "bridge" arrangement 125

are the same in this case as indicated in connection with Fig. 4.

Fig. 7 shows one-half of the two-way repeater circuit, the omitted part being entirely symmetrical in construction, and is a further modification in the wiring of the transformer associated with line H, in that primary windings 5 and 6 of this transformer have been made part of the "bridge" arrangement, instead of being wired in series with each other and either in series or in parallel with the "bridge" arrangement, as previously shown. With this arrangement the primary windings 1 and 2 of circuit D_2 may be wired as one diagonal of the "bridge," the other diagonal being directly connected to line H. The secondary windings of circuit D_2 are wired in series with each other and with relay C_2 . The secondary windings 7 and 8 of the transformer are wired in series with each other and with the energizing portion of repeater A_1 . The condition of balance for the "bridge" is obtained, as is well known, when

$$\frac{Z_1}{Z_2} = \frac{Z_3}{Z_4}$$

where

Z_1 = impedance of reinforcing portion of repeater A_2 ;

Z_2 = impedance of "balancing" electrical circuit B_2 ,

Z_3 = impedance of primary winding 6 when its associated secondary winding is closed through as shown in Fig. 7.

Z_4 = impedance of primary winding 5 when its associated secondary winding is closed through as shown in Fig. 7.

As a particular case for a condition of balance, we may choose to make

$$\frac{Z_1}{Z_2} = \frac{Z_3}{Z_4}$$

Under these conditions it would be preferable to use a balancing repeater B_2 of the same type and characteristics as repeater A_2 , to make primary winding 5 equal in every respect to primary winding 6, and to make the two secondary windings, respectively associated with primary windings 5 and 6 equal to each other in every respect.

Fig. 8 shows a slight modification of the arrangement of Fig. 7, the secondary windings of the transformer associated with line H and with repeater A_1 , being associated together in parallel relation with each other and with repeater A_1 . The conditions of balance for the "bridge" are the same as for the arrangement shown in Fig. 7.

Fig. 9 shows another modification of the arrangement of Fig. 7 the secondary windings 3 and 4 of circuit D_2 being wired in

parallel instead of in series, as shown in Fig. 7. The conditions of balance for the "bridge" are the same as indicated for the arrangement of Fig. 7. Fig. 10 is a further modification of the arrangement shown in Fig. 8, the only change being in the secondary windings 3 and 4 of circuit D_2 being wired in parallel instead of in series, as shown for the arrangement of Fig. 8. The conditions of balance for the "bridge" are the same as for the arrangement of Fig. 7.

Fig. 11 is a still further modification of the two-way repeater circuit of Fig. 1, the only change residing in the association of the primary windings 5 and 6 of the transformer associated with line H, being wired in the "bridge" arrangement proper, in series with windings 1 and 2 respectively, of automatic control relay circuit D_2 . The conditions of balance for the "bridge" are the same as indicated in connection with Fig. 1, except that the impedance as designated as Z_1 and Z_2 include, in addition, the impedance of primary winding 5 (with its associated secondary windings closed through in the manner shown in the drawing) and the impedance of primary winding 6 (with its associated secondary winding closed through as shown in the drawing), respectively.

Fig. 12 shows a modification of that shown in Fig. 11, the two secondary windings respectively associated with primary windings 5 and 6 being wired in parallel with each other and with repeater A_1 , instead of in series with each other and with repeater A_1 . The "bridge" balance relation is the same in this case as for the arrangement of Fig. 11.

The arrangement shown on Fig. 13 is a further modification of that shown on Fig. 11, in that windings 3 and 4, of automatic control relay circuit D_2 are wired in parallel instead of in series, as shown for the arrangement of Fig. 11. The general "bridge" balance condition is somewhat complicated in this case. A specific case of balance is secured when balancing repeater B_2 is made equal in type and electrical constants to repeater A_2 , the two primary windings 1 and 2 are made equal to each other, the two corresponding secondary windings 3 and 4 and furthermore, primary winding 5 is made equal in every respect to primary winding 6, and the corresponding secondary windings 7 and 8 are made equal to each other in every respect.

In all the arrangements shown from Fig. 7 to Fig. 13, the association of the windings 5 and 6 with the "bridge," as shown, introduces a "differential" effect which is of advantage in making more difficult the establishment of reactive influences in the two-way repeater circuit arrangement. It

will be clear upon examination of these arrangements that while, for instance, on incoming non-amplified speech currents reaching the two-way repeater circuit via line H,
 5 the electromotive forces induced in the secondary windings associated with the energizing portion of repeater A₁ are in the same direction and therefore cumulative in their effect, on the contrary, on amplified
 10 speech currents traveling in the opposite direction, the electromotive forces induced in these same windings are opposite in direction and tend, therefore, to neutralize each other.
 15 A number of various arrangements, all satisfying however the same fundamental requirement, have been shown on drawings 4 to 13. Some of these arrangements will prove more advantageous than others in
 20 actual practice, depending upon the line conditions to be met and the electrical characteristics of the apparatus that may be available for use in given instances. A great number of other modifications will
 25 readily occur to those who are versed in the art of telephony. As a general indication in this connection, it may be stated that if the combination of the reinforcing portion of one repeater, the balancing electrical circuit of this repeater and the automatic control relay circuit windings associated with the above in a "bridge" balance arrangement, is assumed to represent "the transmitter" in the usual telephone sub-station set,
 30 35 and the transformer with its primary windings and its secondary windings connected with the energizing portion of the other repeaters is assumed to represent the "receiver" in the same sub-station set, then
 40 one can combine this transmitter and this receiver in practically as many ways as there are known or possible type of telephone sub-station circuits. I have only shown some of the most important and characteristic arrangements, embodying the same underlying principle of "bridge" balance in Figs. 1 to 13. Extensive departures may therefore be made along the broad lines indicated, from the specific arrangements
 45 50 illustrated herein, without departing from the spirit of the invention.

It will be noted that in all cases the terminating telephone stations connected with lines G and H are normally in full repeating relation in either direction and therefore the two-way repeater circuit is ready for instant service, no prior operation of voice operated or manually operated switching means being required.

60 Claims:—

1. In a telephone system between two terminating stations, the combination with two telephone repeaters at each repeating station, each arranged for one-way repeating,
 65 but in opposite direction respectively to the

said telephone system, both normally in full repeating relation to the said system, of voice actuated circuit making and breaking devices and circuit changing means controlled by the same for rendering inoperative that telephone repeater which is arranged for repeating in a direction opposite to the direction of transmission from the talking to the listening station. 70

2. In a telephone system between two terminating stations, the combination with two repeaters at each repeating station, each arranged for one-way repeating but in opposite directions respectively to the said system, a supplementary set of devices for magnifying voice currents, circuit making and breaking arrangements associated with the above devices, responsive to the magnified voice currents, circuit changing means controlled by the above circuit making and 80 breaking arrangement for varying, establishing and maintaining appropriate repeating relations from the talking to the listening station. 85

3. In a telephone system between two terminating stations, the combination with two repeaters at each repeating station, each arranged for one-way repeating but in opposite directions respectively to the said telephone system, both normally in full repeating relation to the said system, of electromagnetic relays responsive to voice currents, circuit changing means controlled by the same for rendering inoperative that telephone repeater which is arranged for 90 repeating in a direction opposite to the direction of transmission from the talking to the listening station. 95

4. In a telephone system between two terminating stations, the combination with two repeaters at each repeating station, each arranged for one-way repeating but in opposite directions respectively to the said telephone system, both normally in full repeating relation to the said system, of devices for converting and amplifying voice currents into unidirectional currents, direct current relays responsive to the unidirectional currents thus obtained, circuit changing means controlled by the direct current relays for rendering inoperative that telephone repeater which is arranged for repeating in a direction opposite to the direction of transmission from the talking to the listening station. 100 110

5. In a telephone system between two terminating stations, the combination with two repeaters at each repeating station, each arranged for one-way repeating but in opposite directions respectively to the said telephone system, both normally in full repeating relation to the said system, of an "audion" arranged for converting and amplifying voice currents into unidirectional currents, direct current relays responsive to 115 120 125 130

the unidirectional currents thus obtained, circuit changing means controlled by these direct current relays for rendering inoperative that telephone repeater which is arranged for repeating in a direction opposite to the direction of transmission from the talking to the listening station.

6. In a telephone system between two terminating stations, the combination with two repeaters at each repeating station, each arranged for one-way repeating but in opposite directions respectively to the said telephone system, both normally in full repeating relation to the said system, of two "bridge" arrangements, each "bridge" arrangement respectively comprising the transmitting circuit of telephone repeater, the transmitting circuit of a "balancing" telephone repeater, an automatic controlling circuit with its associated circuit making and breaking device, and line connections to one of the two terminating stations in such a manner that for non-amplified voice currents reaching the "bridge" over the line connections, the circuit making and breaking device will be in a position of electrical equilibrium in its corresponding "bridge" arrangement and will therefore remain unoperated, while for amplifying outgoing currents reaching the same "bridge" arrangement via the transmitting circuit of the corresponding telephone repeater associated with it, the same circuit making and breaking device will not be in a position of electrical equilibrium and will, when operated, render inoperative, through the circuit changing means it controls, that telephone repeater which is arranged for repeating in a direction opposite to the direction of transmission from the talking to the listening station.

7. In a telephone system between two terminating stations, the combination with two repeaters at each repeating station, each arranged for one-way repeating but in opposite directions respectively to the said telephone system, both normally in full repeating relation to the said system, of two "bridge" arrangements each "bridge" arrangement comprising respectively the transmitting circuit of one telephone repeater, the transmitting circuit of a "balancing" repeater, the primary windings of a transformer with its secondary windings connected to the energizing circuit of the other telephone repeater, an automatic controlling circuit with its associated circuit making and breaking device, and line connections to one terminating station in such a manner that for incoming non-amplified currents reaching the "bridge" arrangement over the line connections the electromotive forces induced in the transformer secondary windings connected to the energizing circuit of the repeater last mentioned, will be cumu-

lative in their effect, the circuit making and breaking device being associated in a position of electrical equilibrium in the "bridge" arrangement remaining unoperated under the same condition; while for amplified voice currents reaching the same "bridge" arrangement through the transmitting circuit of the first mentioned telephone repeater, the electro-motive forces induced in the two transformer secondary windings will be differential in their effect, thus further reducing any possible tendency toward the establishment of reactive influences in the two-way repeater system, so that the circuit making and breaking device under this condition, not being in a position of electrical equilibrium, will, when operated, render inoperative that one of the telephone repeaters which is arranged for repeating in a direction opposite to the direction of transmission from the talking to the listening station.

8. Two circuits and two-way repeating apparatus comprising amplifying means normally conditioned for transmission in either direction between said circuits, and means responsive to initial transmission in either direction to discontinue such condition for transmission in the opposite direction; whereby transmission is effected in either direction without initial hiatus or reflexion.

9. Two circuits and two-way repeating apparatus comprising amplifying means normally conditioned for transmission in either direction between said circuits, and a supplementary set of one-way amplifying means, associated with circuit making and breaking arrangements, responsive to initial transmission in either direction to discontinue such condition for transmission in the opposite direction; whereby transmission is effected in either direction without initial hiatus or reflexion.

10. Two circuits and two-way repeating apparatus comprising amplifying means normally conditioned for transmission in either direction between said circuits and circuit changing means controlled by electromagnetic relays responsive to initial transmission in either direction to discontinue such condition for transmission in the opposite direction; whereby transmission is effected in either direction without initial hiatus or reflexion.

11. Two circuits and two-way repeating apparatus comprising amplifying means normally conditioned for transmission in either direction between said circuits, and devices for converting and amplifying voice currents into unidirectional currents, direct current relays operative by the unidirectional currents thus obtained, circuit changing means, controlled by the direct current relays, responsive to initial transmission in either direction to discontinue such condi-

tion for transmission in the opposite direction; whereby transmission is effected in either direction without initial hiatus or reflexion.

5 12. Two circuits and two-way repeating apparatus comprising amplifying means normally conditioned for transmission in either direction between said circuits, and "audion" type devices arranged for converting and 10 amplifying voice currents into unidirectional currents, direct current relays responsive to the unidirectional currents thus obtained, circuit changing means, controlled by these direct current relays responsive to initial 15 transmission in either direction to discontinue such condition for transmission in the opposite direction; whereby transmission is effected without initial hiatus or reflexion.

18. Two circuits and two-way repeating 20 apparatus comprising amplifying means normally conditioned for transmission in either direction between said circuits, and two "bridge" arrangements, each "bridge" arrangement respectively comprising the 25 transmitting circuit of one one-way telephone repeater, the transmitting circuit of a "balancing" telephone repeater, an automatic controlling circuit with its associated circuit making and breaking device, and line 30 connections to one of the two circuits in such a manner that for non-amplified voice currents reaching the "bridge" over the line connections, the circuit making and breaking device will be in a position of electrical 35 equilibrium in its corresponding "bridge" arrangement and will therefore remain unoperated, while for amplified outgoing currents reaching the same "bridge" arrangement via the transmitting circuit of the 40 responding telephone repeater associated with it, the same circuit making and breaking device will not be in a position of electrical equilibrium and will, when operated, in response to initial transmission in the direction 45 last indicated, discontinue such condition for transmission in the opposite direction; whereby transmission is effected in either direction without initial hiatus or reflexion.

14. Two circuits and two-way repeating 50 apparatus comprising amplifying means normally conditioned for transmission in either direction between said circuits, and two "bridge" arrangements, each "bridge" arrangement comprising respectively the 55 transmitting circuit of one one-way telephone repeater, the transmitting circuit of a "balancing" repeater, the primary windings of a transformer with its secondary windings connected to the energizing circuit 60 of a second one-way telephone repeater, an automatic controlling circuit with its associated circuit making and breaking device, and line connections to one circuit in such a manner that for incoming non-amplified currents reaching the "bridge" arrangement 65 over the line connections, the electromotive forces induced in the transformer secondary windings, connected to the energizing circuit of the repeater last mentioned, will be cumulative in their effect, the circuit making and 70 breaking device, being associated in a position of electrical equilibrium in the "bridge" arrangement, remaining unoperated under the same condition; while for amplified 75 voice currents reaching the same "bridge" arrangement through the transmitting circuit of the first mentioned telephone repeater, the electromotive forces induced in the two-way transformer secondary wind- 80 ings will be differential in their effect, thus further reducing any possible tendency toward the establishment of reactive influences in the two-way repeater system, the circuit 85 making and breaking device under this condition not being in a position of electrical equilibrium, will, when operated in response to initial transmission in the direction last indicated, discontinue such condition for transmission in the opposite direction; 90 whereby transmission is effected in either direction without initial hiatus or reflexion.

In testimony whereof I affix my signature in presence of two witnesses.

MIHRAN M. DOLMAGE.
